UNITED STATES PATENT OFFICE.

BENJAMIN F. SPRY, OF DES MOINES, IOWA.

HORSESHOE.

1,203,068.

Specification of Letters Patent. Patented Oct. 31, 1916.

Application filed September 20, 1915. Serial No. 51,676.

To all whom it may concern:

Be it known that I, BENJAMIN F. SPRY, citizen of the United States of America, and resident of Des Moines, Polk county, Iowa, have invented a new and useful Horseshoe, of which the following is a specification.

The object of this invention is to provide an improved construction for horseshoes, particularly to the end of prolonging the effective life of the shoe by provision for renewing the calks thereon.

A further object of this invention is to provide means for adjusting or fitting a malleable cast-iron horseshoe.

15 A further object of this invention is to provide an improved construction for a heel-plate adapted to be mounted on a horseshoe.

My invention consists in the construction, arrangement and combination of elements 20 hereinafter set forth, pointed out in my claim, and illustrated by the accompanying drawing, in which—

Figure 1 is a plan and Fig. 2 a bottom plan of the complete shoe in its original form, one of the heel calks being removed in Fig. 2. Fig. 3 is a rear end view of one side of the shoe. Fig. 4 is a bottom plan of the shoe as provided with certain of the improved devices for renewing the calks, and 30 with my improved heel-plate. Fig. 5 is a front end view and Fig. 6 a side elevation of the same. Fig. 7 is a bottom plan of another form of my improved heel-plate. Fig. 8 is an edge view of the same, partly in section.

35 This invention relates to and is an improvement on devices illustrated, described and claimed in Letters Patent of the United States granted to me December 6, 1898, No. 615,317, to which patent reference hereby is made.

In the construction of the device as shown particularly in Figs. 1, 2 and 3, the numeral 10 designates a horseshoe bar or plate preferably formed and constructed of malleable cast-iron, with a toe-socket 11 and heel-sockets 12, 13 cast thereon and integral therewith. The toe-socket 11 has its greatest dimension transversely of the toe portion of the bar or plate 10, which is substantially U-shape in plan, and the front and rear walls of said socket preferably are curved to correspond approximately to the curvature of said bar or plate. A toe-calk 14 is formed of a single block of wood, with the grain arranged vertically, shaped and fitted to the socket 11 and driven and frictionally

held therein and projecting slightly beyond the lower margins of said socket. The heel-calks 15, 16 are similarly formed and mounted in the sockets 12, 13, and said sockets 60 preferably are formed with inner walls projecting beyond the margin of the bar or plate 10, leaving apertures 10^a therebetween as shown. Wedge-shaped slugs 17 may be driven into any or all of the wooden calks 65 14, 15, 16 as desired during icy or sleety weather, and may be removed as soon as the occasion for their use is past, to save unduly marring and injuring the pavement. It has been demonstrated that the wooden 70 calks afford an excellent footing on slippery pavement, but when ice is present in any quantities, it is desirable to use the wedges 17 to roughen the surfaces of the calks. An arcuate slot 18 is formed in and through the 75 inner margin of the toe portion of the bar or plate 10, and a V-shaped slot 19 leads from the central portion of said arcuate slot transversely of and nearly across the said bar or plate. This arrangement of slots 80 makes it possible to bend and adjust the bar or plate 10 and fit it to the foot of the animal on which the shoe is to be used, thus removing one of the greatest objections to the malleable cast-iron shoe as commonly 85 used. This arrangement of slots permits the bar or plate 10 to be bent in either direction somewhat, to either greater or less curvature, and does not impair the effective strength of the shoe. 90

In the construction shown in Figs. 4, 5 and 6, a supplementary calk 20 is employed after the wooden calk 14 and its socket have been worn down to such an extent as to materially reduce the effectiveness of the shoe. 95 The supplementary calk 20 is formed of a piece of thin metal bent or folded to channel form and mounted between the remnants of the front and rear walls of the socket 11, and secured to the bar or plate 10 with 100 screw-bolts or rivets 21, through holes 22 originally formed therein. It is to be understood that the supplementary calks 20 may also be used for the rear sockets 12, 13 in a similar manner, if desired. Or a heel- 105 plate 23 may be mounted across the entire rear portion of the bar or plate 10, being suitably secured at its ends to the opposite end portions thereof and bridging the space therebetween, and passing over the apertures 10^a, the inner walls of the sockets 12, 13 having by this time been worn entirely 110

away to said apertures. The heel-plate 23 preferably is formed of transversely extending laminations, and the base lamination may be of metal or heavy leather, while the 5 tread lamination is composed of leather or rubber, both of which form excellent tread surfaces for certain conditions, especially in summer time.

In the construction according to Figs. 7 10 and 8, the tread lamination 23^a, which may be of leather or rubber, is formed with a plurality of perforations 24 extending entirely through it. A quantity of coal-tar or 15 pitch, indicated by the numeral 25, is poured between the bottom layer 23^a and the layer next adjacent thereto, and fills the holes 24. Some of this coal-tar or pitch 25, through the weight of the animal and through the 20 entrance of small pebbles and other foreign substances, is forced out of the holes 24 and forms a coating on the tread surface of the heel plate, and this coating, together with such quantities of dust and the like as adhere thereto, not only assists in forming a 25 reliable tread surface, but also adds materially to the life of the heel-plate by taking

the wear and abrasion therefrom, as the said layer 23^a does not then contact directly with the ground or pavement.

The means shown and described herein for 30 renewing the calks of the shoe adds considerably to the effective life of the shoe, and consequently makes it cheaper for the user. The laminated heel-plate overcomes the greater part of the soreness apt to ensue to 35 the unprotected feet of a horse on city pavements. Altogether this improvement makes it possible to equip a draft animal for any climate or any time of year.

I claim as my invention—

In a horseshoe, a heel-plate comprising a laminated bar, the tread member thereof being formed with perforations, and a viscous substance mounted beneath said tread member and within said perforations.

Signed by me at Des Moines, Iowa, this 9th day of August, 1915.

BENJAMIN F. SPRY.
